Patented Apr. 22, 1975

234,978

CHECK PERFORATOR

Roger Olmazu, Long Island, N.Y., assignor to Integrated
Control Systems, Inc., Great Neck, Long Island, N.Y.

Filed June 8, 1973, Ser. No. 368,173

Term of patent 14 years

Int. Cl. D19—02

U.S. Cl. D64—10

FIG. 1

FIG. 2

FIG. 3

FIG. 4

FIG. 5

FIG. 1 is a top plan view of a check perforator, showing my new design;

FIG. 2 is a left end elevational view thereof;

FIG. 3 is a bottom plan view thereof;

FIG. 4 is a rear elevational view thereof; and

FIG. 5 is a front elevational view thereof, with only the first or front row of pins shown for purposes of clarity.

I claim:

The ornamental design for a check perforator, as shown and described.
